CLAIM

The ornamental design for a housing for an electronic
device, as shown.

DESCRIPTION

FIG. 1 is a front isometric view of a new design for a housing
for an electronic device.

FIG. 2 is a front side elevation view of FIG. 1.

FIG. 3 is a back side elevation view of FIG. 1.

FIG. 4 is a right side elevation view of FIG. 1.

FIG. 5 is a left side elevation view of FIG. 1.

FIG. 6 is a top plan view of FIG. 1; and,

FIG. 7 is a bottom plan view of FIG. 1.

The features shown in broken lines in the drawing depict
portions of the part of the housing for an electronic device
and form no part of the claimed design.

1 Claim, 7 Drawing Sheets
